2 Claims. (Cl. 246—74)

Controlling devices which cause an automatic application of the brakes of a railway train wherein the track is not clear, are usually combined with and operated by means of a signaling system and are very complicated and costly.

The object of the present invention is to obtain a train-controlling system which is of a very simple construction and which will nevertheless effectively protect trains from accidents due to wrongly set points and wrongly despatched trains and even floods, collapsed bridges and the like.

With this object in view the invention consists essentially in combining the switch points or their operating levers with means for connecting an electric track contact located at the approach to the station to earth through control contacts in the station, so that, unless there is concerted action between the official in charge of the station and the man in charge of the points, the train will not be admitted, said track contact being arranged so as to be swept by a contact rail on the train which rail, if the contact should be earthed, causes the brakes to be applied in known manner. There are also track contacts inside the station which insure in the same manner that no train will enter a track already occupied and that no train will leave the station unless the track is clear.

Fig. 1 of the accompanying drawing represents a diagram of the track lay-out at one side of the station and shows the electric connections;

Fig. 2 is a diagrammatic view of the electric brake-operating device of the train;

Fig. 3 is an enlarged view of one of the point-operating levers and the electric contacts operated thereby; and

Fig. 4 is a diagram of an additional circuit.

The track lay-out illustrated in Fig. 1 is that located at one side of a station on a single line track. The main track branches out at the station into four tracks A₃, A₂, A₁ and A₄. Out of these, the tracks A₂ and A₁ are arrival tracks, as indicated by the arrows, A₃ is a departure track for trains leaving towards the left, and A₄ is a dead track which is only used for shunting.

The train is provided with an electric brake circuit comprising a battery *d*, a magnet *s* and an armature *r* which latter operates, by means of a lever *g*, the valve of the air brake *f*. One end of the magnet coil is connected permanently to earth through the wheels and through the track. The other end of the coil is connected to one pole of the battery *d* the opposite pole of which is connected to a contact rail *e*. When

this rail is temporarily connected to earth through contacts on the track, the brake circuit will be closed and the brake applied.

One such track contact *a*, provided with contact rings *k*, is arranged at the approach to the station, and it is connected through a wire *m* to a switch lever *4* located in the control room *C* of the station. The switch points *b*, *b*₁ and *b*₂ whereby the different tracks are brought into use, are each operated by means of a lever *p* arranged as illustrated in Fig. 3. The lever carries an electric contact *3* which is permanently connected to earth and which sweeps two stationary contacts *1* and *2* as it is moved from one end position into the other. In each end position of the lever one of the stationary contacts remains connected through the contact *3* to earth, the other being disconnected. Thus in the position shown by full lines in Fig. 3, the contact *1* is connected to earth. When the lever is moved into the position shown by dotted lines, the contact *1* will be disconnected, and the contact *2* will be connected to earth.

The levers *p* are located in a signal box *D*. The lever which operates the first switch point *b* has its contact *1* connected by means of a wire *t*₁ to a wire *m*₃, and its contact *2* is connected to wire *t*₂ to the wire *m*. The second lever, which operates the point *b*₁, has its contact *1* connected to a wire *m*₁, while the contact *2* is connected to a wire *m*₂. Both of these latter wires terminate in control contacts arranged in the room *C*, so that either of them can be connected to the wire *m* by means of the switch lever *4*. The lever *p* which controls the point *b*₂ connects a contact *t*₃ with the wire *m*₁ when the point is operated for admitting a truck or wagon on to the track A₄.

Where the trains stop inside the station there are track contacts *av*₃, *av*₂, and *av*₁, one for each of the tracks A₃, A₂ and A₁ respectively. The contact *av*₃ is connected to the wire *m*₃, and the contacts *av*₂ and *av*₁ are connected to contacts *i*₂ and *i*₁ respectively in the control room *C* where a switch *z*₁ is provided for connecting either track contact to earth. The same switch is used for earthing a wire *os*' which leads to the neighboring station at the right. Additional track contacts *o*₂ and *o*₁ inside the station are connected to the wires *m*₂ and *m*₁ respectively. These additional track contacts are earthed by a train which is stationary inside the station.

A wire *os* which, like the wire *m*₃, leads to the neighboring station at the left, leads in the con-

trol room C to a switch by means of which either of these wires may be connected to earth.

The principal track contact *a* has also an earthing circuit *t* which is closed by the semaphore signal B when the latter is on "stop".

In the diagram of Fig. 1, the arrangement is such that an incoming train will be free to enter the station track A₂. If any re-arrangement should be made, the brake circuit of the 10 train will be earthed and closed through the track contact *a*. Such earthing will take place through the signal B if the latter should be on "stop". If the point *b* should be in the wrong position, the wire *t₂* will be connected to earth through the 15 lever *p*, and the brake circuit will thus be earthed and closed through the latter wire and through the wire *m*. If the point *b₁* should be in the wrong position, the wire *m₂* will be earthed through the 20 contact 2 of the respective lever *p*, and the brake circuit will be closed through said wire, lever 4, wire *m* and contact *a*. When the train arrives on the track A₂ in the station, it engages the track contact *o₂* and thus earths the contact *a* through the wire *m₂*, lever 4 and wire *m*, and if another 25 train should arrive, it will be stopped at the contact *a*. However, this train may be admitted on to the track A₁ if the point *b₁* is reversed and if the lever 4 is connected to the wire *m₁* instead of *m₂*. When both trains are in the station they 30 will be protected from further incoming trains, since the contact *a* is then earthed through the wire *m*, lever 4, wire *m₁* and contact 2 of the respective point operating lever *p*. Normally the contact *a* and the wire *m* are earthed by the lever 35 4 at *z* so that no trains can enter the station.

For a train to leave the station in the direction to the left by way of the track A₃, the contact *av₂* must be disconnected from earth in the control room C. However, the contact *av₃* may also be 40 earthed from the neighboring station through the wire *m₃*, in which case the train can only leave after it has been freed by the official in the latter station. In the same manner, a train ready to 45 leave the neighboring station, can be detained by the official in the room C by the earthing of the wire *os*. For a train to leave the station towards the right the respective track contact *av₂* or *av₁* must be disconnected from earth. This is effected by means of the switch lever *z₁* which at 50 the same time connects the wire *os'* to earth so as

to prevent a train from leaving the neighboring station in the opposite direction.

Where there is a bridge or where floods are likely to occur, contacts may be arranged which in case of a flood or the collapse of the bridge, 5 earths the wires *m₃* and *os* and thus prevents a train from leaving the station.

A similar arrangement to that shown in Fig. 1 is provided at the right-hand side of the station.

When the station is provided with an automatic signalling system for incoming trains, this system may be brought into use as shown in Fig. 4. The signalling wire 8 leads to a magnet 6 in the control room C. A switch lever 7, which is operated by the magnet, earths the wire *m* and the track contact *a* through a contact 5 when the signal is operated, and thus no train can enter the station while the signal is on.

We claim:

1. In an automatic train controlling system, 20 the combination with the switch point operating levers of a railway station of a pair of electric point contacts for each lever, means on the lever for connecting said point contacts alternately to earth when the lever is reversed, an electric brake 25 circuit on the train permanently connected to earth and including a contact rail, an outside track contact at the approach to the station and a track contact on each track inside the station all adapted to be swept by said contact rail, a 30 group of control contacts, wires connecting individual control contacts with individual point contacts, means for connecting the track contacts in the station to earth and to control contacts of neighboring stations, means for connecting the outside track contact to different point contacts and to earth through the different control contacts, additional track contacts in the station adapted to contact with and to be earthed by the train, and means for connecting said additional track contacts through the control contacts to 35 the outside track contact as a protection for the train while it remains in the station.

2. The automatic train signalling system claimed in claim 1 in combination with an earthing circuit for the outside track contact, and a 40 semaphore signal adapted to close said earthing circuit when the signal is on "stop".
